UNITED STATES PATENT OFFICE.

JAN MANKOWSKI, OF GARRETT, INDIANA.

PARACHUTE APPARATUS.

1,115,705.

Specification of Letters Patent.

Patented Nov. 3, 1914.

Application filed August 4, 1914. Serial No. 855,022.

To all whom it may concern:

Be it known that I, JAN MANKOWSKI, a subject of the Czar of Russia, residing at Garrett, in the county of Dekalb and State 5 of Indiana, have invented certain new and useful Improvements in Parachute Apparatus, of which the following is a specification.

This invention relates to new and useful 10 improvements in parachute apparatus and especially to that class of such devices adapted to be attached to the body of the aeronaut.

The primary object of the invention is a 15 provision of a foldable umbrella shaped parachute member which is readily secured to the person, and easily folded and unfolded by the wearer.

A further object of the device is to provide 20 a number of rib formations hinged adjacent the chest of the person, each of said ribs being downwardly and inwardly foldable upon themselves, and whereby a depending closed parachute is positioned beneath the arms of the aeronaut.

A still further object is to provide a 25 parachute hinged surrounding the person and directly beneath the arms, and having an attachment to the arms whereby the oblique as well as the folding position of the device 30 may be readily governed.

With these objects in view and others that will appear as the nature of the invention 35 is better understood, the same consists in the novel combination and arrangement of parts hereinafter fully described, illustrated in the accompanying drawings and pointed out in the appended claims.

In the drawings forming a part of this 40 application and in which like-designating characters refer to corresponding parts throughout the several views,

Figure 1 is a front elevation of the framework of the device with some of the ribs 45 moved and others broken away. Fig. 2 is a top plan view thereof with all of the ribs removed. Fig. 3 is a top plan view of the complete device. Fig. 4 is a perspective view of one of the ribs detached, and broken 50 away. Fig. 5 is a detail enlarged view of the hinged end of one of the ribs, and, Fig. 6 is a detail top plan view of the hinged portions of the collar.

Referring more in detail to the drawings 55 the device broadly consists in the umbrella

canopy 10 preferably formed of fabric or waterproof material, and having a serviceable means for removably detaching the same to the body of a person and in a foldable position.

For attaching the canopy to the body, a yoke member 11 is provided, having a collar 12 for encircling the neck and with oppositely extending shoulder-receiving extensions 13, which latter are arched or channel-shaped in cross-section and adapted to rest on the shoulders. The collar 12 is open at the front, and is divided into two equal parts which are connected together by a hinge 14 positioned centrally at the back of the collar. A chest band 15 is connected to the extensions 13, and is secured to the collar by means of connecting strips 16, being adapted to encircle the body around the chest thereof, the entire yoke so formed being secured in position by means of straps 17 connected between the opposite strips 16.

A waist belt 18 is connected to the band 15 by means of adjustable connecting straps 19. A plurality of eyes 20 are mounted 80 upon the outer face of the belt 18 and are equally spaced apart, while a corresponding number of pairs of spaced-apart lugs 21' are mounted upon the outer face of the chest band 15, and correspond in number to the 85 eyes 20, each of said pairs being equally spaced apart.

A plurality of ribs 21 have their inner ends 22 hinged to the lugs 21', and are provided with spaced eyes 23 on their undersurfaces. Each of the ribs 21 is provided with a hinge 24 substantially midway of its length, and whereby the lower portion of each rib is inwardly and downwardly foldable against the undersurface of the upper 95 rib portions. Adjustable cords 25 have their ends secured to the rib eyes 23 and slidably pass through the belt-eyes 20. The canopy 10 is secured to the upper surfaces of the ribs 21 which ribs extend substantially radially beneath the canopy. The canopy is severed radially at the front thereof as at 26, and is in a direct line with the severing of the collar and with the separating line between the opposite strips 16. The opposite 105 sides of the canopy are connected together by means of securing straps 27.

The upper side of the canopy is provided with arm straps or loops 28, and outwardly thereof with hand hold loop 29, the 110

line of the rib hinges 24 being positioned between the loops 28 and 29.

The complete operation of the device will be apparent from the above detailed description in that the yoke is secured around the upper portion of the body by means of the strap 17 and the belt 18 is secured in place, and the canopy thus removably attached to the body of the aeronaut, and whereby he may safely descend from high altitudes, such as from a balloon, aeroplane, bridge, or any other elevated position. The arms of the wearer are extended through the inner loops 17 and the hands grasped the outer loops 29 so that by changing the position of the arms, the position of the ribs and the canopy are readily positioned at the desirable inclination. By moving the lower portions of the ribs inwardly upon the hinges 24, the lower outer or marginal portion of the canopy is inwardly positioned between the body of the wearer and the inner faces of the upper or inner portions of the ribs. In this position, the arms and hands may be disconnected from the canopy loops, and the device worn around the upper portion of the body without inconveniencing the wearer in manipulating his aircraft. When desired for use, the arms and hands may be readily engaged the loops, and whereupon the lower portion of the canopy is readily unhinged and the entire canopy spread out for immediate use.

While the forms of the invention herein fully described are what are believed to be preferable embodiments thereof, it is nevertheless to be understood that minor changes may be made in the form and proportion of the various parts without departing from

the spirit and scope of the invention as set forth in the claims.

What I claim as new is:—

1. A device of the class described comprising a yoke adapted to be supported by the person, and having a hinged collar, a chest band, and connecting laterally extending shoulder engaging members, a plurality of ribs equally spaced apart and hinged to said band, a canopy secured to the upper surfaces of said ribs, and encircling said band, a waist belt, connecting straps between said belt and band, two eyes carried by the under surfaces of each of the ribs, a plurality of eyes carried by said belt, and cords running through the said belt eyes and having their opposite ends secured to the eyes of the adjacent rib.

2. A device of the class described comprising a yoke adapted to be removably attached to the upper portion of the body of a person, a belt strap, two-part hinged ribs having their inner ends equally spaced apart and hinged to the said yoke, eyes carried by each portion of said ribs, eyes carried by said belt, cords slidably positioned through said belt eyes and having their ends secured to the eyes of the adjacent rib, a canopy covering the said ribs, arm loops oppositely positioned upon the top of said canopy, and inwardly of the hinged connection between the rib portions, and hand holds carried by said canopy outwardly of said loops.

In testimony whereof I affix my signature in presence of two witnesses.

JAN MANKOWSKI.
